UNITED STATES PATENT OFFICE

EUGENE LOUIS EZBELENT, OF PARIS, FRANCE

PLAITING MACHINE

Application filed August 31, 1925, Serial No. 53,705, and in France April 18, 1925.

The machines in current use for the obtainment of plaited work comprise an upper and a lower plaiting blade which are continuous and have the same length as the machine. 5 The movements of the two blades are combined, and they will produce either overlapping knife plaits or underlapping knife plaits, according as they are made to follow one of two plates respectively termed "upper 10 formation plate" or "lower formation plate"; they will further produce box plaits when they are made to follow alternately the said upper and lower plates. In all cases, by virtue of the continuous form of the plaiting 15 blades, the plaits or folds will be of the same character over all the length of the fold.

My invention has for its object an improved plaiting machine affording the obtainment of patterns, designs and folds 20 which are reversed in the lengthwise direction of the fold. Said machine is chiefly characterized in that it comprises a plurality of pivoted plaiting blade elements disposed upon the length of the machine, and that 25 certain of the said elements may be given different movements relatively to the others.

Various other features of the invention will be set forth in the following description with reference to the appended drawings, 30 given by way of example, and relative to an embodiment of the said invention.

Fig. 1 is a section of the machine with the plaiting blades in the front position, and

Fig. 2 is a like view with the plaiting 35 blades in contact with the formation plates.

Fig. 3 is a diagrammatic plan view of the lower plaiting blades.

Fig. 4 is a diagrammatic elevation of an 40 arrangement affording the lengthwise motion of the set of plaiting blade elements.

Figs. 5, 6 and 7 illustrate portions of fabric plaited upon a machine provided with the device according to the invention.

Figs. 8 and 9 are sections, respectively corresponding to Figs. 1 and 2, of a modification of the machine according to the invention, the control members being not shown, these being of known types, and

Figs. 10 and 11 are like sections of another modification.

As is shown in Figs. 1 and 2 the machine comprises two frames 1 and 2, having the form of angle pieces, and carrying rigidly preferably near their ends two steel blades 3, 3' which may form either plaiting plates or stoppers limiting the movements of said frames when said blades come into contact with the usual upper and lower formation plates 10 and 11 of the machine; said frames extend over all the length of the cylinders, and the lower frame 2 carries at each end two standard plates 4 in which the upper frame 1 is journaled at 5. The plates 4 are provided with journals 6 which are given a straight reciprocating motion towards and away from the cylinders as usual for the blades of plaiting machines.

A C-shaped member 7 is secured (Fig. 1) to the upper frame 1 and is supported through the medium of a roller 8 upon a plate 9 which may be raised during the rearward stroke of the journals 6 and of the frames 1 and 2 away from the cylinders as is usual in well-known plaiting machines. This will provide for the rotation of the frame 1 upon the journal 5 together with the blades 3' mounted thereon. A suitable shaft 13 extending over the whole length of the frame 2 may be rotated by known controlling means, such as are shown at 12, Figs. 1 and 2.

Between the two blades 3 of frame 2 and the two blades 3' of frame 1 are disposed the two sets 14, 14' of plaiting blade elements which are respectively secured to the sets of blade carriers 15 and 16; the carriers 15 are rotatable on the shaft 13 whilst the carriers 16 are rotatable on the shaft 17. In Figs. 1 and 2, the carriers 15 can be set upon the shaft 13 by means of the set screws 18, and when thus held, the said carriers together with their plaiting blade elements 14 will be rotated with the shaft 13.

In this manner, certain of the plaiting blade elements may occupy at will the upper position and other elements the lower position; the former, coacting with the upper formation plate 10, will produce the overlapping folds of the plaited work, and the latter, coacting with the lower formation plate 11 will produce the underlapping folds,

so that I may reverse the fold or plait at any chosen point, lengthwise of the said folds of the work.

In case all the plaiting blade elements of each set are secured in one and the same plane to the shaft 13 by the screws 18, the plaited work obtained will be analogous to the work produced upon the current type of machines, i. e. according to the upper or the lower position of the operating means 12, I may produce the same plait, either an overlapping knife plait, or an underlapping knife plait, or box plaits, throughout the whole length of the plait, lengthwise of the fold.

15 The upper frame 1 is notched at 19 to provide for the ascent of the said plaiting blade elements. The spring 20 urges each upper plaiting blade element downward and causes the same to enter into contact with a lower plaiting blade element. In this manner each upper element will cause the opposite lower element to descend when the latter is not controlled, and when the said lower element is controlled, it will in turn cause the upper element to rise.

During the rearward stroke of the frames 1 and 2, in order to allow the fabric to be fed through the cylinders, it is necessary that the blade elements 14 and 14' become opened. It has already been stated above that the upper frame 1 and the blades 3" are raised during the rearward stroke by means of the C-shaped member 7. During the rotation of the upper frame 1 upon the journals 5 said frame will abut (through the medium of the screw 21) against the rear projection of the upper pivoted blade 16, thereby rotating and raising the latter and thus opening the sets of pivoted plaiting blade elements 14 and 14'.

42 For the obtainment of patterns of chevron or other forms, as shown by way of example in Fig. 7, the whole arrangement of blades and blade carriers may be longitudinally displaced with an alternating motion.

45 I may produce the said displacement as follows:

To the end of the control shaft 22 is keyed a suitably shaped cam 23 whereof the bosses will lower the roller 24 carried by a lever 25 and will hence pivot the said lever, thus producing a lengthwise reciprocating motion of the plaiting blade elements together with their carriers. This will displace the patterns lengthwise of the folds, and the amount of the displacement will vary according to the outline given to the cam 23.

By rendering the said cam loose on its shaft, the reciprocating motion will cease, and I obtain a class of straight line patterns analogous to what are shown in Figs. 5 and 6.

Obviously, the number and length of the fixed blades 3 and 3' and the plaiting blade elements 14, 14' may be chosen as desired.

The modifications of the machine according to the invention respectively illustrated

in Figs. 8 and 9 and in Figs. 10 and 11 offer the material advantage that it is possible therewith to modify the nature of the folds made by each blade element, during the course of the work and without stopping the machine.

For this purpose, and as shown in Figs. 8 and 9, while the upper blade carriers are rotatably mounted on the shaft 17, as in Figs. 1 and 2, the lower blade elements 14 are secured to the respective blade carriers 26, mounted loose on the shaft 13 supported by the frame 2. Each blade carrier 26 is provided with a pivot joint 28 to which is attached the rod 29 which is controlled by the link 30 which is rotatable on the shaft 31 supported by the frame 2 and extending all over the same.

A set of levers 32, respectively corresponding to the various links 30, are pivoted upon a rod 33, each of said levers carrying two rollers 34 and 35. A drum 36 having the same length as the machine, is provided with circular rows of holes respectively situated in the vertical planes containing the rollers 34, whereby removable cam elements or bosses 37 may be secured to said drum according to needs; the drum may be given an intermittent rotary motion, for instance by a ratchet device, so that it is rotated through half the angular space between two consecutive holes of one row at the end of the forward and rearward strokes of the lower frame, each hole, or the cam element engaged therein, being in line with the roller 34 of the corresponding arm 32 during the forward stroke of said lower frame.

When the blade elements are at the end of the forward stroke (Fig. 8) the levers 32 occupy the position shown in the said figure. The drum 36 has rotated in such manner that each roller 34 is situated between two bosses 37, or between two consecutive apertures of the drum. The rollers 35 are in the lower position and have no action upon the levers 30, this condition prevailing during the whole rearward motion of the blade elements.

When the said blade elements have attained the end of the rearward stroke (Fig. 9) the drum 36 is rotated through a certain angle; if a boss 37 comes under a roller 34, the same will be raised, as also the corresponding roller 35 together with the lever 30, so that the pivot 28 will be lowered and the blade element thus controlled will be raised to its upper position. The said blade element will produce an overlapping knife plait. But if there is no boss below the roller 34, the corresponding blade element will remain in its lower position and will produce an underlapping knife plait. At the end of the forward stroke, the drum 36 will be rotated through a certain angle, and the cycle of operations thus continues.

It will be thus observed that a given boss

37, secured by means of its shank in an aperture in the drum 36, will cause the corresponding blade element to produce an overlapping knife plait, whilst in the absence of 5 said boss the same blade element will produce an underlapping knife plait.

In this manner, it will be understood that if the bosses 37 are distributed according to 10 a certain disposition upon the drum, a corresponding pattern or design composed of overlapping plaits and underlapping plaits will be automatically produced on the plaited work by the said blade elements.

The bosses 37 may be readily secured to 15 the drum 36 and may be disposed thereon according to a great variety of patterns. It is to be observed that the use of narrower blade elements will further increase the diversity 20 of the combinations in the patterns or designs which may be produced.

In the modification shown in Figs. 10 and 11 the lower blade elements 14 may be raised at will by means of the following device:

25 For the shafts 17 and 13 of the preceding figures are substituted two tubes 41 and 43, connected together at their ends by two end plates 4 similar to that shown in Figs. 1 and 2; the rotation of the upper tube 41, for 30 opening the blades, is controlled by a C device, not shown and similar to member 7 (Figs. 1 and 2), while the motion of the lower tube 43 is controlled by known controlling means, not shown, similar to that shown at 35 12 (Figs. 1 and 2).

The lower blade elements 14 are supported by blade carriers 42, rotatable on the tube 43 and which are each provided with a pin or 40 stud 46 extending and adapted to slide through the same; said stud is urged outwardly by a spring 47, and when the latter is compressed, the stud may engage in a corresponding aperture 48 in the tube 43. When 45 the stud is in the position shown in Fig. 10, the corresponding blade element will be loose on the tube. The corresponding upper blade carrier 40, which is urged into its lower position by the spring 20, will oblige the lower blade element to assume its lower position, 50 thus providing for the formation of an underlapping plait.

The insertion of the studs 46 into the tube 43, for connecting together the said tube and the blade carrier 42, is controlled by cam elements or bosses 37 disposed in circular rows 55 upon a rotary drum 36 similar to that shown in Figs. 8 and 9 and to which a continuous or intermittent motion may be imparted; each row of cam elements corresponds to one pin or stud 46, and the cam elements of one row 60 may control the inward motion of the corresponding pin 46 through the medium of a rocking arm 32 mounted loose on a common shaft 33 and provided with a roller 34 situated in the same plane as the cam elements 37.

Each of the latter may be removably secured upon the drum for instance by means of a shank adapted to engage a hole provided in the periphery of the drum.

When a boss 37 engages the roller 34 of 70 one lever 32, the latter will be raised, thus causing the stud 46 to enter the recess 48 in the tube 43. The corresponding blade element 42 is thus connected by the stud with the tube 43 and will hence follow the movements of the latter and will produce either 75 overlapping plaits or underlapping plaits. If there are no bosses engaging the roller 34, the corresponding blade element will produce an underlapping plait.

Fig. 11 shows blade carriers 42^a which are connected by their studs with the tube 43 and thus are in a position corresponding to the formation of overlapping plaits, and other blade carriers 42^b which are loose on the tube 43 and are in a position corresponding to the formation of underlapping plaits.

It will be observed also that upon the whole length of the tube 41 is a groove 44 in which engage stop screws 45 respectively carried by the blade carriers 40. When the C device rotates the tube 41, the latter will drive at a certain moment, the screws 45 of all the blade elements, so that the latter will be opened. The said groove 44 has sufficient width so that 90 when the C device is inoperative, the blade elements may assume the upper or the lower position.

Obviously, in the machines illustrated in 95 Figs. 8 to 11, I may substitute for the drum with removable bosses, a band, for instance of cardboard, which is either perforated or is provided with removable bosses, and which is movable below the control levers, thus serving the same purpose as the above 100 described drum.

Having now described my invention, what I claim as new and desire to secure by Letters Patent is:

1. In a plaiting machine an upper and a lower longitudinal frame, on each of said frames a plurality of plaiting blade elements and means whereby said frames may be displaced together longitudinally with respect to the cylinders of the machine.

2. A plaiting machine of the character described, comprising in combination a pair of pressing rollers and at least one reciprocating plaiting knife blade having an edge which coacts with the pressing rollers, some 110 portions of said edge being displaced relative to other portions thereof whereby some portions of each plait are formed in a reverse direction to the other portions.

3. A plaiting machine of the character described, comprising in combination a pair of pressing rollers, a pair of plaiting knife blades having their edges divided, means for displacing some portions of said divided edges of the knife blades relative to other por- 115 120 125 130

tions, said plaiting knife blades being reciprocable to and from the said pressing rollers whereby some portions of each plait are formed in a reverse direction to the other portions.

4. A plaiting machine of the character described, comprising in combination a pair of plaiting rollers, a pair of reciprocating plaiting knives having their forward edges divided into fingers, means for selectively displacing some of said fingers upwardly and others downwardly whereby along the length of each plait some portions are formed in a reverse direction to other portions.

5. A plaiting machine of the character described, comprising in combination a pair of plaiting rollers, divided plaiting blades disposed between said rollers at one side thereof, said blades having the forward edges of some of the divided parts displaced relative to the other parts whereby some parts of each plait are folded upwardly and others downwardly.

6. In testimony whereof I have signed my name to this specification.

EUGENE LOUIS EZBELENT.
